UNITED STATES PATENT OFFICE.

ELLSWORTH C. STEVENS, OF SPRINGFIELD, MASSACHUSETTS.

IMPROVEMENT IN TIPS FOR SPRING-BARS OF VEHICLES.

Specification forming part of Letters Patent No. **154,812**, dated September 8, 1874; application filed July 25, 1874.

To all whom it may concern:

Be it known that I, ELLSWORTH C. STEVENS, of Springfield, in the county of Hampden and State of Massachusetts, have invented a new and valuable Improvement in Cap for Spring-Bar; and I do hereby declare that the following is a full, clear, and exact description of the construction and operation of the same, reference being had to the annexed drawings, making a part of this specification, and to the letters and figures of reference marked thereon.

Figure 1 of the drawing is a representation of a top view of my device. Fig. 2 is a horizontal sectional view. Fig. 2' is a detail.

The nature of my invention consists in a metallic ornamented cap for the end of a spring-bar used in carriages, which cap, as well as the end of the bar, receives through it the bolt which passes through the goose-neck or body-supporter, and thereby makes a substantial connection, as will be fully understood from the following description.

In the annexed drawings, A designates my improved cap, and B one end of a spring-bar. The mode of finishing the ends of spring-bars hitherto adopted is to ornament them by carving the wood, which is expensive, and leaves the ends very weak, so much so that very few

spring-bars on carriages which have been used for any length of time are found to be perfect. I construct the cap A of metal, with a deep socket in it to receive the tapered end of the bar B. I am thus able to furnish highly-ornamented caps which are not liable to be broken, and which are very cheap. The upper portion of the cap has an extension, b, formed on it, through which a screw is passed that secures the cap on the spring-bar. The rectangular portion or butt of the cap is perforated, and a hole, a, made through the bar B to receive the bolt which secures the neck C to the bar. Thus it will be seen that the cap affords a durable metallic bearing for said neck and its bolt.

What I claim as new, and desire to secure by Letters Patent, is—

A metallic cap, A, having a socket to receive the tapered end of the spring-bars of carriages, substantially as set forth.

In testimony that I claim the above I have hereunto subscribed my name in the presence of two witnesses.

ELLSWORTH C. STEVENS.
